UNITED STATES PATENT OFFICE.

JOB VIALL, OF SCHAGHTICOKE, NEW YORK.

DESIGN FOR AN ICE-CREEPING PLATE.

59,308.

Specification for Design.

Patented Oct. 4, 1921.

Application filed November 11, 1919. Serial No. 337,268. Term of patent 14 years.

To all whom it may concern:

Be it known that I, JOB VIALL, a citizen of the United States, residing at Schaghticoke, in the county of Rensselaer and State of New York, have invented a new, original, and ornamental Design for Ice-Creeping Plates, of which the following is a specification, reference being had to the accompanying drawing, forming part thereof.

Figure 1 of the drawing is a view in perspective seen from above of an ice-creeper-plate embodying my design.

Fig. 2 is a similar view of the plate inverted.

I claim:

The ornamental design for an ice-creeper-plate as shown.

JOB VIALL.
